UNITED STATES PATENT OFFICE.

HENRY L. BERNHARDT, OF MILWAUKEE, WISCONSIN.

DIRECTIONAL SIGNAL.

1,286,509.

Specification of Letters Patent.

Patented Dec. 3, 1918.

Application filed November 10, 1917. Serial No. 201,345.

To all whom it may concern:

Be it known that I, HENRY L. BERNHARDT, a citizen of the United States, residing at Milwaukee, in the county of Milwaukee and 5 State of Wisconsin, have invented new and useful Improvements in Directional Signals, of which the following is a specification.

This invention relates to new and useful 10 improvements in directional signals for motor vehicles, and the principal object of invention is to provide a device operated from the steering-post for indicating to the vehicles following that the driver intends to turn either to the left or the right or he 15 is to stop his car.

Another object of the invention is to make the signals in the form of an arrow and to provide the same with a small lamp whereby 20 the signal may be seen at night, and to locate said arrow adjacent a signal lamp and to provide said lamp with a transparent portion for reflecting the light therefrom onto the arrow.

Another object of the invention is to provide a device of this character which is simple and durable in construction, reliable and efficient in operation and one which can be manufactured and placed upon the market at a minimum cost.

30 The invention also consists in certain other features of construction and in the combination and arrangement of the several parts, to be hereinafter fully described, illustrated in the accompanying drawings and 35 specifically pointed out in the appended claim.

In describing my invention in detail, reference will be had to the accompanying drawings wherein like characters denote 40 like or corresponding parts throughout the several views, and in which:—

Figure 1 is an elevation of an automobile showing the invention applied thereto.

Fig. 2 is a rear view showing the different positions of the signal.

Fig. 3 is a side view of the signal and rear lamp with their supporting bracket.

Fig. 4 is a sectional view on line 4—4 of Fig. 3.

50 Fig. 5 is a detail view of the operating means for the signal.

Fig. 6 is a section on line 6—6 of Fig. 5.

Fig. 7 is a diagrammatic view of the circuit.

55 In these views 1 indicates the automobile and 2 the steering-post thereof. At any suit-

able point on the rear of the body of the automobile I locate the bracket 3 which is of substantially L-shape and has its front end turned upwardly as at 4 to provide a 60 support for the license plate 5. This bracket should be so located that the license plate will receive the light from the tail lamp A. A bolt 6 is carried by the upper part of this bracket and a signal lamp 7 is secured to the 65 outer end of said bolt in any suitable manner. 8 indicates the signal preferably made in the form of an arrow as shown and having its inner end provided with an enlargement 9 which carries a suitable bearing for 70 engaging the bolt and 10 indicates a pulley secured to said enlargement. As will be seen the enlargement and pulley are located between the lamp and the bracket so that the signal is immediately in the rear of the 75 lamp. The signal or arrow is normally held hidden behind the license plate, in its lowermost position by means of a coil spring 11 having one end suitably secured to the bracket and its other end to the signal adjacent the pulley. 12 indicates the operating cable having one end secured to the pulley and passing around the same and over suitable guiding wheels such as 13 to a bell-crank lever 14 secured adjacent the lower 80 part of the steering-post. The other end of this bell-crank lever is connected by a wire 15 to a lever 16 carried by a plate 17 secured to the steering-post within convenient reach of the driver. The lever 16 carries a spring 90 plate 18 on which is an operating button 19 and a pin 20, said pin being adapted to engage holes 21 in the plate 17. By pressing the button the pin may be disengaged from one hole so that the lever 16 may be moved 95 into another position on the plate and thus the signal set at the desired position. It will be understood that the holes in the plate 17 are so arranged and designated that the driver may place the signal in the positions 100 shown on dotted lines in Fig. 2 to indicate that he is to stop or to turn to either the left or the right. The signal is provided with a small electric lamp 22, and this lamp and the signal lamp 7 are suitably connected 105 with a battery B as shown in Fig. 7. Said battery is also connected with a segmental contact 7' on the lamp 7 and a contact 8' on the enlargement 9 of the arrow 8 is adapted to engage said contact 8' when the arrow is 110 moved to complete the circuit and light both lamps. The signal lamp has a trans-

parent portion 23 in its upper part for reflecting the light therefrom onto the arrow when the same is in operative position. 24 indicates a reflector or shield located in front of this opening. The plate 17 may be secured to the steering-post by means of the straps 25 secured to the plate and adapted to embrace the post.

As will be seen in the inoperative position 10 of the signal the arrow lies behind the license plate and is hidden from view. When the driver wishes to turn or stop he may swing the arrow into one of the three positions shown by moving the hand lever on 15 the plate 17 secured to the steering-post.

If desired I may divide the cable 12 into two parts and connect the same together by a coil spring 12'.

It is thought from the foregoing description 20 that the advantages and novel features of my invention will be readily apparent.

I desire it to be understood that I may make slight changes in the construction and

in the combination and arrangement of the several parts, provided that such changes 25 fall within the scope of the appended claim.

What I claim is:—

A device of the class described comprising an L-shaped bracket having its front end turned upwardly and adapted to receive a 30 license plate, a bolt carried by the upper end of said bracket, a signal lamp carried by said bolt, a pulley on said bolt in the rear of the lamp, a cable connected with said pulley and leading to a point adjacent 35 the driver's seat, an arrow having its end connected with said pulley, a spring connected with said arrow and with the bottom of the bracket for holding said arrow behind the license plate and a transparent 40 member in the upper part of the lamp for directing the rays of light on to said arrow when the same is in raised position.

In testimony whereof I affix my signature.

HENRY L. BERNHARDT.
